CRAWL CARRY MECHANISM

Howard M. Fleming, West Orange, N. J., assignor
to Monroe Calculating Machine Company,
Orange, N. J., a corporation of Delaware

Application January 9, 1947, Serial No. 721,004

4 Claims. (Cl. 235—136)

1

The invention relates to calculating machines, and particularly to tens transfer or carry devices of the "crawl" type, such as disclosed in the patent to Gardner, No. 1,828,180, dated October 20, 1931, an object of the invention being to eliminate the coupling between the nine tooth gear and the ten tooth gear of the patent disclosure and gear the nine tooth gear and the ten tooth gear directly together, thereby reducing the number of parts and reducing the backlash inherent in any type of such coupling, the reduction of backlash being important in this type of gear, particularly when used in connection with totalizer mechanisms such as are used in the Monroe listing machine. Another object is to so reduce this backlash that it shall not affect the accuracy of the total taking, the backlash being normalized in each denominational order as the total taking progresses successively from the lower denominational order to the higher orders, one revolution of the coupling used herein (which is for the purpose of coupling together the totalizer wheel gear of lower order to the hub of the eccentric related to the totalizer wheel gear of next higher order), representing a carry of one digit to the next higher order, the parts being always normalized to a common fixed position during each total taking. Another object is to reduce lost motion, simplify the construction, permit simpler tooling and facilitate manufacture. Other objects and advantages will appear hereinafter or will be obvious.

The invention consists in the novel construction and combinations of parts, as hereinafter set forth in the claims.

In the accompanying drawings,

Fig. 1 is a vertical front to rear section of a machine having the invention applied thereto.

Fig. 2 is a section on the line 2—2, Fig. 4.

Fig. 3 is a side view of a totalizer unit of the machine.

Fig. 4 is an end view of the same.

The "crawl" tens transfer means at present used in the Monroe listing machine, for which this invention is designed, is shown in principle in the patent to Gardner aforementioned, which patent and the prior art named therein is made part of this disclosure.

In comparing this invention with that of the said Gardner patent, the action and cooperation of the parts remains unchanged, and given reference numerals refer to corresponding parts, with certain exceptions. The "crawl" tens transfer is effected by a train of orbital gearing of the kind termed "entocyclic" in said Gardner patent.

The patent to Crossman, No. 1,932,013 is referred to for a disclosure of the machine for which this invention is designed to be used.

Each denominational order of the machine is provided with a three armed actuator lever 610, these levers being fulcrumed on a shaft 608. The forward arm of each lever 610 terminates in a segmental registering rack, the rearward arm has a listing type bar 611 pivoted thereto and the upper arm has pivotal connection with a differential stop bar 615 cooperating with a bank of digital keys 215 to limit the movement of the lever 610. The digital keys 215 which have been depressed to represent a value, are latched in position with the bottoms of their stems lying in the path of movement of the related stop lugs of the bars 615, allowing such bars to advance a distance proportional to the value of the key, upon operation of the machine. Depression of a digital key will also remove a column latch 214 from the path of movement of its related bar 615, these latches preventing movement of a stop bar and lever 610 in any column in which no key is depressed.

25 A rock shaft 301 is provided with cam means 318 for governing the movement of a spring tensioned rocker frame 616, mounted on shaft 608, frame 616 carrying a series of dogs 617 normally engaged by studs 659 of the levers 610. As shaft 301 is rotated forwardly, frame 616 will be rocked, and any of the levers 610 which have been released by the depression of digital keys will be allowed to rotate under the influence of their spring 683 until they are stopped by the lugs of bar 615 contacting with the stems of the keys. Upon rearward rotation of shaft 301, the dogs 617 will return the operated levers 610 to normal position. This excursion of the levers 610 serves to register amounts set in the keyboard 40 upon one or more accumulator or totalizer wheels 40 and to set up a similar amount on the printing line of the type bars.

For each denominational order of the machine, with exception of the units order, as will be explained, the totalizer wheel shaft 403 has rotatably mounted thereon a totalizer unit comprising the following.

50 A hub 430 upon which the pinion or actuator gear 472 is rotatably mounted, said hub having at one end thereof an eccentric 430'; a floating totalizer wheel gear 473' rotatably mounted upon said eccentric through the medium of a sleeve 473'' and meshing with said actuator gear 472, the totalizer wheel gear having ten teeth and the actuator gear nine teeth, and coupling members

located respectively at the opposite ends of said unit. These coupling members comprise for each totalizer unit a notched extension of the sleeve 473" related to the totalizer wheel gear of higher order, the notch being designated 471', and a member 470 fast to the other end of said hub and having a long tooth 470' for slidable engagement with the notch 471' of the sleeve extension related to the totalizer wheel gear of next lower order, thereby providing coupling means between the gear of lower order and the hub of the eccentric related to the gear of next higher order.

The sleeve 473" is made fast to the related floating totalizer wheel gear 473' by means of radial extensions 474 of the sleeve riveted at 474' to the totalizer wheel gear, although obviously the sleeve and the floating gear may be made in one piece.

The locator arm 470" made fast to the related hub 430 and acting to hold the eccentric 430' of the units order from rotation is itself made fast to the fixed framing or accumulator end plate 410, as shown in Fig. 2.

Thus the totalizer units are complete with respect to each denominational order, and it is not necessary to add a partial totalizer unit at either end of the series.

Since no carrying ever takes place in the units order, it is essential that the eccentric 430' of that order be held from rotation, and the member corresponding in position to the said member 470 and similarly made fast to the related hub 430, but lacking the tooth 470', is provided with a locator arm 470" utilized for this purpose.

Entocyclic gearing is known, as in the patent to Parsons, No. 601,164, dated March 22, 1898, wherein the totalizer wheel gear is an internal tooth gear and the actuator gear meshing therewith is loosely mounted upon an eccentric fast to the hub of the totalizer wheel gear (just the reverse of the present case), but this construction necessitates greater complication and results in more lost motion, the very things the applicant's construction is designed to avoid.

In the tens carry operation, the eccentric of the units order being held stationary, the units actuator will rotate its actuator gear 472 and the units totalizer wheel gear 473', and the latter having made one complete rotation will through the tooth and notch engagement or coupling between the units and tens orders rotate the hub 430 and eccentric 430' of the tens order once completely, thereby bodily revolving the totalizer wheel gear 473' of the tens order in a circular path the radius of which is the degree of eccentricity of the eccentric 430' of the tens order relative to shaft 403, resulting in the advance of the totalizer wheel gear 473' of the tens order one step of movement to effect the carry. With this explanation the operation of the tens transfer devices from order to order will be obvious.

In taking a total or a sub-total, the corresponding key being depressed, the actuator levers 610 will be released one after another from right to left of the machine, each actuator lever being then driven by its spring to rotate the related totalizer wheel in a subtractive direction; zero stop members 613 being also released successively, each stop member 613 falling into the path of movement of the related 0 stop of the totalizer wheel, the 0 stops of said wheels being constituted by the extensions 471" of the right angle flanges of the sleeves 473" beyond the peripheries of the totalizer wheels. Thus the totalizer wheel is held in zero registering position as the

extension 471" of said flange contacts the related stop member 613.

In order to bring the higher order totalizer wheel into proper position in relation to the zero stop member 613, the eccentric 430' controlled by the lower order totalizer wheel will lift the higher order totalizer wheel towards the zero stop member 613 as the lower order totalizer wheel is brought to zero.

10 I claim:

1. In a register having a series of totalizer wheel gears, and differentially movable actuators therefor; crawl tens transfer devices between said gears comprising actuator gears, a hub upon which the related actuator gear is rotatably mounted, said hub having an eccentric, a floating gear constituted by a totalizer wheel gear rotatably mounted upon said eccentric and meshing with said actuator gear, the number of teeth of the actuator gear and the totalizer wheel gear having a ratio of nine to ten, and coupling means between the totalizer wheel gear of lower order and the hub of the eccentric related to the totalizer wheel gear of next higher order.
- 15 2. In a register having a series of totalizer wheel gears, and differentially movable actuators therefor; crawl tens transfer devices between said gears comprising actuator gears, a hub upon which the related actuator gear is rotatably mounted, said hub having an eccentric, a floating gear constituted by a totalizer wheel gear rotatably mounted upon said eccentric and meshing with the actuator gear, the number of teeth of the actuator gear and the totalizer wheel gear having a ratio of nine to ten, and coupling means between the totalizer wheel gear of lower order and the hub of the eccentric related to the totalizer wheel gear of next higher order comprising a notched member fast to the totalizer wheel gear of lower order and a member fast to the hub of the eccentric related to the totalizer wheel gear of next higher order and having a long tooth slidably engaging the notch of the first named member.
- 20 3. In a register, having a series of totalizer wheel gears, and differentially movable actuators therefor; crawl tens transfer devices between said gears comprising actuator gears, a hub upon which the related actuator gear is rotatably mounted, said hub having an eccentric, a floating gear constituted by a totalizer wheel gear rotatably mounted upon said eccentric through the medium of a sleeve and meshing with the actuator gear, the number of teeth of the actuator gear and the totalizer gear having a ratio of nine to ten, and coupling means between the totalizer wheel gear of lower order and the hub of the eccentric related to the totalizer wheel gear of next higher order comprising a notched extension of the sleeve related to the totalizer gear of lower order and a member fast to the hub of the eccentric related to the totalizer gear of next higher order and having a long tooth slidably engaging the notch of the adjacent sleeve extension.
- 25 4. In a register having a series of totalizer wheel gears and differentially movable actuators therefor; crawl tens transfer devices between said gears comprising actuator gears, a hub upon which the related actuator gear is rotatably mounted, said hub having an eccentric, a floating gear constituted by a totalizer gear rotatably mounted upon said eccentric through the medium of a sleeve and meshing with the actuator gear, the number of teeth of the actuator gear and of the totalizer gear having a ratio of nine to ten,

and coupling means between the totalizer wheel gear of lower order and the hub of the eccentric related to the gear of next higher order comprising a notched extension of the sleeve related to the gear of lower order and a member fast to the hub of the eccentric related to the gear of next higher order and having a long tooth slidably engaging the notch of the adjacent sleeve extension, said sleeve extension having a projection located beyond the periphery of the gear constituting a zero stop. 10
